Mills Company, Inc., Thomasville, N. C.

Application December 14, 1934, Serial No. 757,521

11 Claims. (Cl. 66—9)

This invention relates to a knitting machine and more especially to means for laying in a strand in automatic knitting machines employing cylinder and dial needles.

5 In automatic seamless knitting machines employing both dial and cylinder needles, it is a well known fact that these machines are capable of knitting a welt at the top of the stocking together with a ribbed portion and a leg portion 10 together with heel, toe and foot portions, in other words, knitting a complete stocking with the exception of looping the toe after the stocking is completed on the knitting machine. Other types of dial knitting machines such as ribbed in- 15 verse machines and split foot machines, knit the complete stocking except the welt.

It has been desirable to use elastic yarn in the ribbed top portion of the stocking to make a stocking which will be self-supporting and which 20 will remain in elevated position on the leg of the wearer without the necessity of employing supporters of any kind.

It has been possible to knit elastic yarn in the ribbed top portion but this takes a great quantity 25 of yarn and also greatly decreases the elasticity of the yarn on account of knitting it into the ribbed top portion under tension. It has long been desired to knit the top ribbed portion and to lay the elastic yarn thereinto, but it is a well 30 known fact that this elastic yarn cannot be fed into the needles at the conventional point of feeding because it would result in knitting the yarn into the stocking by use of the dial and cylinder needles.

35 It is, therefore, an object of this invention to provide means whereby the elastic yarn can be laid into the ribbed top portion of the stocking so that the dial needles and the cylinder needles will knit the conventional top yarn around the elastic yarn without engaging the elastic yarn and knitting it in any manner.

Some of the objects of the invention having 40 been stated, other objects will appear as the description proceeds, when taken in connection 45 with the accompanying drawings, in which:—

Figure 1 is an elevation of a portion of a knitting machine showing the cylinder and means for feeding the elastic yarn to a portion of the 50 knitting machine so that it will not be knitted by the cylinder or dial needles;

Figure 2 is a vertical sectional view taken along line 2—2 in Figure 1;

Figure 3 is a view showing the main and pattern drums of the machine for operating the

means for feeding the elastic yarn to the knitting machine;

Figure 4 is an enlarged elevation of the lower end of the feeding finger for the elastic yarn shown in cooperation with some of the cylinder needles;

Figure 5 is a view looking at the left-hand side of Figure 4;

Figure 6 is a top plan view of the dial cap and latch ring, showing the yarn feed finger for the elastic yarn in section;

Figure 7 is an elevation of the top of a stocking made in accordance with my invention;

Figure 8 is an elevation showing the manner in which the elastic yarn is laid into the knitting and showing the loops in the knitting in a greatly separated and distended position;

Figure 9 is a bottom plan view of Figure 8;

Figure 10 is an elevational detail showing dial and cylinder needles engaging the top yarn and showing the elastic yarn being laid in;

Figure 11 is a diagrammatic view looking down on Figure 10 and showing additional loops.

Referring more specifically to the drawings, the numeral 10 indicates a bracket for supporting 25 the dial needle mechanism of the machine which also supports a suitable cross-bar 11 supporting other portions of the knitting machinery. On this cross-bar there is secured a member 12 which heretofore has been provided to form guideways 30

for a yarn feeding finger for feeding yarn to the needles at this point in case of making what is called a "wrap". This comprises the member 12 having notches therein which are closed by plates 13 and 13a forming a groove in which the yarn 35 feeding finger is adapted to have vertical sliding movement. The wrap yarn finger is dispensed with and in lieu thereof a special finger 14 is provided for feeding the elastic yarn to the knitting machine so that it will not be knitted by 40 either of the dial or cylinder needles. The member 12 not only supports the vertically sliding member 14 but also supports a tension spring 15 which normally pulls the yarn feed finger 14 45 downwardly. The yarn feed finger 14 has a laterally projecting pin 16 under which one arm of the bell crank lever 17 is adapted to project, said bell crank lever 17 being pivotally mounted as at 18, and having its other end connected to a link 19 which, in turn, is slidably connected to a lever 20. The lever 20 (Fig. 3) is seen to be 50 fixedly secured to a stub arm 21 on a hub 22 mounted on a shaft 23 and fixedly secured to hub 22 is an arm 24 which is adapted to follow a cam 25 on the auxiliary pattern drum 26 of the 55

knitting machine. Lever 20a is also fixedly secured to arm 21 and is adapted to contact the main pattern drum 27 of the knitting machine and to be moved by a cam 28 thereon.

5 The elastic yarn 30 is fed through a yarn guide 31 and downwardly just inside the latch ring 32. The yarn feed finger 14 likewise projects downwardly just inside the latch ring 32 and just outside the cylinder needles. The dial cap 33 has a 10 dial 34a rotatably mounted therein which has a plurality of dial needles 34 and 35 mounted therein which are controlled by suitable cams not shown. The numeral 34 indicates the hook needles while 35 indicates the cast-off needles. The 15 cylinder 36 of the machine has mounted therein a plurality of cylinder needles 37 which are of the conventional type and each has a pivoted latch 38 thereon.

The yarn feed finger 14 projects downwardly 20 immediately outside the cylinder needles and on account of the close space in which it has to work it must be provided with some means to prevent breakage of the cylinder needles. Accordingly, the lower end of the yarn feed finger 25 has a V-shaped cam having surfaces 40 and 41 terminating in a point 42. This point 42 is slightly above the pivot points of the latches for the cylinder needles, so that it is seen that the cam surfaces 40 and 41 will serve to either open or 30 close the latches of the cylinder needles as they pass thereby and, therefore, prevent breakage of the same. This is very important.

The lower end of the yarn feed finger 14 projects in the direction of travel of the dial and 35 cylinder of the machine and projects downwardly and inwardly at the same time and has an eye 44 therein through which the elastic yarn 30 is passed so as to deliver the yarn to the needles at a point where no knitting will occur and at 40 a point below the dial needles and below the latches of the cylinder needles so that it will not be engaged thereby and at a point where the cylinder needles will likewise not engage it so that the cylinder needles will engage alternate 45 loops on the ordinary yarn and the dial needles will engage the other loops so that the strand is knitted across the elastic strand in the manner shown in Figures 8 to 11 inclusive without either the cylinder or dial needles knitting the elastic 50 yarn but merely laying it in, in the manner shown and described.

The dial cap 33 has the conventional leaf spring 55 yarn clamp 45 thereon. It also has the conventional movable yarn clamp 46 thereon which is operated in a conventional manner. It also has conventional shears 47 thereon which are also operated in a conventional manner. The clamp 46 and the shears 47 are operated by suitable instrumentalities, not shown, controlled by the 60 auxiliary pattern drum when the elastic yarn is withdrawn from laying in position.

The dial cap has its upper surface beveled on the side next to the throat plate 48 and the 65 yarn fingers 49. In order to introduce the elastic 70 yarn at a thin place in the dial cap where it will traverse the cylinder needles, I mount a pin 50 in the dial cap to prevent the elastic yarn from passing over the high edge of the dial cap and being held where it will not be engaged by the cylinder needles when it is introduced to laying in position.

In Figure 1 the elastic yarn is shown after it has been introduced and has passed completely 75 around the cylinder and has passed inside the

cylinder needles at the throat plate and is being laid in.

Although Figure 2 is taken along line 2-2 in Figure 1, the elastic yarn 30 is shown in a different position, being in the position it occupies 5 when first lowered to a position where it will be caught by one of the cylinder needles, as it is seen that in introducing the elastic yarn, it is passed between two cylinder needles and being held by the spring clamp 47 a cylinder needle will 10 carry the elastic yarn around to knitting position where the end of the elastic yarn is pulled from beneath the spring clamp. Although the elastic yarn may be caught and knitted by one or two needles, the subsequent cylinder needles will not 15 knit in the elastic yarn for the reason that it fed at a point below the pivot point of the latches and on top of the sinkers which will move it outwardly out of the path of the descending hooks of the cylinder needles. 20

It will be observed in Figure 3 that the pattern drum 27 serves to lower the yarn feed finger when the lever 20 falls into the cavity in the cam surface, but it is also evident that this main drum cannot be used for throwing the elastic yarn out 25 of position where it will be laid into the fabric because it would interfere with the knitting of the top which will usually stop many courses after the elastic yarn has ceased to be laid in, and therefore, means are provided whereby the auxiliary pattern drum can be employed for throwing the elastic yarn out of operation after a pre-determined number of courses of elastic yarn have been laid into the ribbed top. 30

Let us assume that the cavity appearing in the 35 cam surface 28 of Figure 3, represents the length of the top of the stocking. Therefore, the auxiliary pattern drum 26 will throw the elastic yarn out of operation long before the main drum 27 has moved far enough for cam 28 to engage the 40 lever 20a and therefore the auxiliary pattern drum will throw it out of operation and not interfere with the top of the stocking. 45

In Figure 7 a finished top is shown as made on one type of machine in which usually a small 50 welt W will be knitted and then the yarn feed finger 14 will be automatically lowered and the portion E will have the elastic yarn laid thereinto, which will be withdrawn long before the top ribbed portion has been completed and the remainder of the top will be knitted of ordinary ribbed fabric by the dial and cylinder needles but without laying the elastic yarn therein, although it is evident that the entire ribbed portion could have a yarn either elastic or otherwise, laid therein, if desired. 55

It is also well understood in the art, that in knitting ribbed fabric that alternate cylinder needles are used with all of the dial needles, as there are twice as many cylinder needles as dial needles and by using half of the cylinder needles only, then the dial needles pass between the cylinder needles and engage the knitting yarn between the cylinder needles thus resulting in alternate loops being engaged by the hook dial needles and the other loops are engaged by the cylinder needles. 60

The elastic yarn is threaded through the yarn feed finger 14 and placed under the conventional clamp and in front of pin 50 and when the elastic 65 yarn finger is lowered one of the cylinder needles engages the elastic yarn because from pin 50 to eye 44 it goes in front of one of the cylinder needles. The needle and possibly another, receives the same in their hooks to be knitted in 70 75

along with the top yarn at the knitting point and then the yarn is carried around on the outside of the cylinder needles and when it reaches the throat plate, where the conventional knitting 5 operation takes place, the conventional knitting occurs which consists of a course of the top yarn being engaged by alternate cylinder needles as only one-half of the cylinder needles are in operation during this operation and the hooked 10 dial needles move out between the cylinder needles and engage the top yarn and pull the alternate loops back against the dial and then the alternate cylinder needles form their loops. At this point, the cylinder needles being lowered, 15 allow the elastic yarn to pass in and rest on the loops held by the hooked dial needles. On the next revolution, the elastic yarn being laid on all of the loops held by the hook dial needles for a complete revolution, the second and subsequent 20 knitting operations take place on the second and subsequent revolutions of the knitting machine which repeats the above described operation, that is, the cylinder needles engage the top yarn and at the same time the hook dial needles 25 and the cast-off dial needles move out and the hook dial needles engage the strand of yarn being knitted and the cast-off needles cast off the loops held by the cast-off dial needles onto the loop being formed at that time by the hooked dial 30 needles.

It is thus seen that the elastic yarn is not knitted except at its ends but is laid in between the wales formed by the dial needles and the cylinder needles.

35 In Figures 8 to 11 inclusive, there is shown the manner in which the elastic strand is laid in the knitting of the ribbed top. It is seen that the cylinder needles 37 engage the top yarn *t* and that the dial needles 34 and 35 engage the top 40 yarn between the loops formed by the cylinder needles and Figure 10 shows the hook and cast-off dial needles in position where they move their loop outwardly over the laid in elastic yarn to a point where the hook needle 34 will engage the 45 next course of top yarn *t* and then the cast-off needle will cast off the already formed loop onto the new loop being formed by the hook dial needle. This lays the elastic yarn in between the wales formed by the dial needles and the 50 wales formed by the cylinder needles. The knitting of the dial and cylinder needles is in the conventional manner, but a description of same has been made in order to show how the elastic yarn is laid in during this ribbing operation.

55 The cylinder needles form the loops *c*, while the dial needles form the loops *d*.

In the drawings and specification, there has been set forth a preferred embodiment of the invention, and although specific terms are employed they are used in a generic and descriptive sense only, and not for purposes of limitation, the scope of the invention being set forth in the appended claims.

When the ribbed top of a stocking is knitted on 60 a Scott & Williams model HH knitting machine it is customary to use alternate cylinder needles and all of the dial needles. It will be noted by referring to Figure 1 that the conventional dividing cam 31b engages the butts 31a of the low 65 needles 37 and forces these needles downwardly immediately before these needles reach the point of introduction of the elastic yarn 30, whereas, the alternate high needles are disposed at such an elevation that their butts 31a will pass over cam 70 75 31b. This cam will prevent the hooks of the

alternate low needles from engaging the strand 30 at any time.

By referring to Figure 6 it is seen that the end of the elastic strand 30 is held beneath clamp 45 when the lower foot portion of member 14 is in a raised or inoperative position, and when the foot portion is in this raised position, the eyelet 44 in the lower end thereof is located slightly above the dial cap 33. When the foot portion is lowered to operative position, which is shown in Figures 1 and 2, the eyelet is disposed below the latches 38 of the high needles and the strand 30 occupies the position relative to the needles, shown in Figure 2, when it is first introduced. It is, therefore, seen that the strand 30 traverses the path of the needles at a point above the latches 38 and beneath the hooks when the yarn is first introduced. Since one end of the strand 30 is clamped the upper portion of the high needles, which first engages the strand, will carry the strand 30 around to the knitting point, holding the strand below the hooks and above the latches of the first few successive needles. As a matter of fact, immediately before the first needles which engage the strand, lower to knit, the end of the strand is held by the clamp, from which the strand leads directly below the hook and above the latch of said first needle, and then the strand passes spirally downwardly on the outside of the needles to the eyelet 44. This spiral inclination makes it possible for several of the hooks to engage the strand before the strand is low enough to be disposed beneath the latch. After the first few needles which engage the elastic yarn have been moved downwardly, to cause the same to knit, the strand 30 occupies a horizontal position below the latches 38, as shown in Figure 1, instead of an upward inclined spiraled position, as is the case when the yarn is introduced and just prior to knitting the end thereof. This upward spiraled position is shown in dotted lines in Figure 1.

It is evident that when the elastic yarn is knitted by a few needles and the strand occupies a horizontal position beneath the latches, that these needles cannot engage the elastic yarn when they move downwardly to knit, but instead the latches 38 will be closed and the strand will pass over the tops of the needles 37 the knitting point and be laid on top of the loops formed by the dial and alternate cylinder needles.

Therefore, it is seen that if the first raised needle engaging the elastic yarn should have its latch closed the next succeeding raised needle or needles having an open latch will engage and knit the elastic yarn.

Likewise, when the elastic yarn is withdrawn by the raising of the member 14 a few of the hooks of the high needles engage the yarn as it is retired since the eyelet 44 is raised above the tops of the high needles the strand will again be caused to traverse the path of the needles at a point above the latches and below the hooks to cause two or three needles to knit the elastic strand as it is withdrawn.

The latches in the needles will be entirely open if the machine is operating properly by having top yarn fed thereto, and the conventional latch opener in the machine is functioning properly, and the needles are being lowered properly by the needle leveling mechanism. Now if the top yarn breaks, or the needles are not leveled or lowered properly due to some imperfection of the machine, resulting in the latches not being entirely open but occupying a position below a horizontal plane passing through the pivot point of the

latch, then the lower cam surface 41 will complete the opening of the latches. If the latches should be projecting upwardly but not entirely closed, then of course, it is evident that they could not take the elastic yarn and the upper cam surface 40 would completely close these latches resulting in an imperfect knitting, but it would prevent the needles and latches of the machine from being broken.

10 I claim:

1. In a knitting machine having a main drum and an auxiliary pattern drum and revolving dial and cylinder needles, means for clamping the end of a yarn on the dial, means for feeding the yarn to the exterior of the cylinder needles and below the latches of the cylinder needles at a point in advance of the throat plate of the machine whereby the yarn will not be engaged by the hooks of more than one or two of the cylinder needles, but will be laid in between the loops formed by the respective cylinder and dial needles, means controlled by the main drum of the knitting machine for throwing the yarn into position to be laid into the knitting of the fabric, and means controlled by the auxiliary pattern drum for withdrawing the yarn from laying-in position.

2. In a knitting machine having revolving dial and cylinder needles, a yarn feed finger for feeding an elastic strand to the exterior of the cylinder needles before they reach knitting position and at a point disposed below the pivot point of the latches of the cylinder needles and below a horizontal plane passing through the lower edge of the dial needles, so the elastic strand will ride over the tops of the cylinder needles when they are lowered in a knitting operation and rest on the loops held on the dial needles, said yarn feed finger having a pointed edge adapted to be engaged by the latches of the cylinder needles to open or close said latches and to prevent breakage thereof.

3. In an automatic knitting machine having rotating cylinder and dial needles, means for laying in an elastic strand during the knitting of a ribbed top portion comprising a yarn feed finger for feeding the elastic strand to the exterior of the cylinder needles at a point below the pivot point of the latches on the cylinder needles and at a point in advance of the cylinder needles reaching knitting position at the throat plate, means for opening or closing the latches of the cylinder needles immediately before they reach the point where the elastic strand is fed, the elastic strand being laid on top of the loops held by the dial needles when the cylinder needles are lowered for knitting of the top yarn and the elastic strand being carried around on top of the loops being held by the dial needles during the succeeding revolution of the dial and cylinder needles to cause the loops of the dial needles to be knitted above the elastic strand without knitting the elastic strand.

4. In a knitting machine having cylinder and dial needles, means for laying in a strand of yarn between the loops formed by the cylinder and dial needles which comprises means for feeding the strand of yarn to the exterior of the cylinder needles and below the latches thereof at a point before they reach knitting position, means for opening or closing the latches of the cylinder needles immediately before they reach the point where the elastic strand is fed whereby the strand passes over the top of the cylinder needles when they are actuated in a knitting operation

to rest on the loops formed by the hooked dial needles and the cylinder needles and upon the subsequent knitting operation to have the loops on the dial needles passed over the strand while the dial needles engage the knitting yarn and form new loops through the loops cast off by the dial needles to thereby lay in the strand.

5. That method of knitting on an automatic knitting machine having revolving cylinder and dial needles, which comprises opening or closing the latches of the cylinder needles, and while the latches are opened or closed, laying an elastic strand on the outside of the cylinder needles below the latches thereof before they are lowered into knitting position whereby the elastic strand will pass over and to the inside of the cylinder needles and rest on the loops held by the dial needles to be laid in between the loops formed by the cylinder and dial needles of the machine.

6. That method of laying in an elastic strand on a knitting machine having revolving dial and cylinder needles which comprises knitting with alternate cylinder needles and all of the dial needles, opening or closing the latches of the cylinder needles, and while the latches are opened or closed, feeding an elastic strand to the exterior of the cylinder needles and below the latches thereof and before they reach knitting position whereby the elastic strand will pass over the cylinder needles and will rest on the loops being held by the dial needles and will be laid in between loops formed by the alternate cylinder needles and all of the dial needles when they again reach their knitting position.

7. In a knitting machine having a given number of cylinder needles and one-half as many dial needles as cylinder needles, and in which ribbed knitting is effected by use of alternate cylinder needles and all of the dial needles, means for opening or closing the latches of the cylinder needles and holding said latches in open or closed position, means for feeding a strand of yarn to the exterior edge of the cylinder needles and below the latches thereof and at a point before they are advanced to knitting position and while the latches of the cylinder needles are held in open or closed position so that the strand will pass over the tops of the cylinder needles onto the loops on the dial needles when the cylinder needles are lowered in their knitting operation, and whereby the strand will be laid in between the wales formed by the alternate cylinder needles and the dial needles.

8. A knitting machine having a revolving dial equipped with cast-off and hook needles and also having a revolving cylinder equipped with cylinder needles, means for clamping an end of an elastic strand on the dial and means for feeding an elastic strand to a point below the latches of the cylinder needles and on the exterior of the cylinder needles means for opening the latches of the cylinder needles and holding said latches in opened position until the elastic strand is laid against the exterior of the cylinder needles, whereby the elastic strand is passed between two of the cylinder needles while they are in raised position and so that the elastic strand will be knitted into the fabric for a loop or two when the cylinder needles are lowered in a knitting operation and the remainder of the elastic strand will pass over the tops of the cylinder needles and be laid onto the loops held by the cylinder needles and the hook needles.

9. A knitting machine having a revolving dial

equipped with cast-off and hook needles and also having a revolving cylinder equipped with cylinder needles, means for clamping an end of an elastic strand on the dial, means for opening or closing the latches of the cylinder needles, means for lowering to a point on the exterior of the needles below the latches of the cylinder needles while their latches are held in open or closed position whereby the elastic strand is passed between two of the cylinder needles while they are in raised position and so that the elastic strand will be knitted into the fabric for a loop or two when the cylinder needles are lowered in a knitting operation and the remainder of the elastic strand will pass over the tops of the cylinder needles and be laid onto the loops held by the cylinder needles and hook needles, and the elastic strand will be knitted into the fabric by the cylinder needles for a loop or two when it is withdrawn from lowered position.

10. That method of knitting with a knitting machine having a revolving dial equipped with cast-off and hook needles and also having cylinder needles revolving in timed relation with the dial which comprises opening or closing the latches of the cylinder needles, clamping an elastic strand on the dial and lowering the elastic strand at a point in advance of the knitting position of the cylinder needles to where it engages the exterior of the cylinder needles at a point below the latches of the cylinder needles while they are held in opened or closed position whereby the elastic strand is knitted by one or two of the cylinder needles when it is introduced to and withdrawn from the cylinder needles and whereby the elastic strand rides over the upper ends of the cylinder needles when they are lowered in a knitting operation and is laid onto the loops held by the hook needles.

15. In a knitting machine having revolving cylinder and revolving dial needles, cam means for opening or closing the latches of the cylinder needles and holding them in such position for a portion of a revolution of said machine, means for clamping an elastic strand on the inside of the circle defined by the dial needles, means for feeding the elastic strand to the exterior of the cylinder needles in advance of the knitting point and below the latches of the cylinder needles whereby the elastic strand is knitted by one or more cylinder needles when they reach knitting position and will then pass over the other cylinder needles without being knitted and will rest on the loops held by the cylinder and dial needles.
